UNITED STATES PATENT OFFICE.

WALTER H. THOMAS, OF SPENCER, IOWA.

FOOT ACCELERATOR.

Application filed June 1, 1926. Serial No. 112,879.

The object of my invention is to provide a foot accelerator control of simple, durable and comparatively inexpensive construction.

More particularly my invention relates 5 to a foot accelerator adapted to have parts mounted upon the hand throttle control rod and capable of being shifted longitudinally thereon, whereby carburetors arranged in different positions relative to the hand 10 throttle control rod may be operated changing only the position of the parts of the foot accelerator.

It may be here mentioned that with certain makes of carburetors now used upon 15 Ford automobiles the connection between the hand throttle control rod and the carburetor is near the lower end of the hand throttle control rod while in other makes of carburetors the connection is near the 20 upper end of the hand throttle control rod and it is my object to provide a foot accelerator having parts mounted upon the hand throttle control rod and capable of being reversed longitudinally thereon so 25 that the same part when in one position will co-operate with a connection near the lower end of the hand throttle control rod and when in another position will co-operate with a connection near the upper end of 30 the hand throttle control rod, the foot actuatable member which operates the part on the hand throttle control rod being the same and in the same position regardless of the 35 position of the other parts of the foot accelerator.

Still a further object is to provide a foot accelerator for operating a throttle link when such link is either connected to the hand throttle control rod near the lower end 40 thereof or near the upper end thereof, the foot actuatable member being positioned relative to the hand throttle control rod at a point substantially midway between the normal connection of the throttle link with 45 the lower and upper portions of the hand throttle control rod.

Still a further object is to provide in a 50 foot accelerator, a member mounted upon the hand throttle control rod of an automobile and capable of being reversed thereon end for end so that the bottom end when in one position may be the top end allowing such end to assume two different 55 positions upon the hand throttle control rod.

It may be here mentioned that in some 60 types of carburetors for Ford automobiles,

the hand throttle control rod is connected to the carburetor by a link or rod extended through the block of the engine itself, while in other types the connecting link extends 60 over the engine block, and it is my object to provide a foot throttle control capable of being used upon either type of carburetor by simply reversing the longitudinal position of a fitting upon the throttle control 65 rod.

With these and other objects in view, my invention consists in the construction, arrangement and combination of the various 70 parts of my foot throttle control, whereby the objects contemplated are attained, as hereinafter more fully set forth, pointed out in my claims, and illustrated in the accompanying drawings, in which:

Figure 1, is a top plan view of a portion 75 of an automobile with my improved foot accelerator installed thereon parts being shown in section to better illustrate the construction.

Figure 2, is a perspective view of the hand 80 throttle control rod, steering shaft and spark controlling rod of an automobile with parts of my foot accelerator mounted thereon.

Figure 3, is a similar view with the same 85 parts reversed for co-operation with a carburetor of a different type from that intended for use when the parts are in the position shown in Figure 2.

Figure 4, is a sectional view taken on line 90 4—4 of Figure 3.

Figure 5, is a detail sectional view taken on line 5—5 of Figure 2.

Figure 6, is a detail sectional view taken 95 on line 6—6 of Figure 3; and

Figure 7, is a perspective view of the fitting 100 adapted to be mounted upon the throttle control rod.

In the accompanying drawings I have used the reference numeral 10 to indicate generally an automobile body which includes 105 a floor board 12 and the engine 14. A hand throttle control rod 16 is adapted to be connected to a carburetor mounted upon the engine 14 for operating the throttle lever 18 of the carburetor 20.

A steering rod 22 and a spark control rod 24 are positioned along the hand throttle control rod 16. An arm 26 is fixed to the hand throttle control rod 16 and is designed to normally be connected with the throttle 110 lever 18 by the link 28.

When my improved foot accelerator is

used then the link 28 is disconnected from the crank arm 26 and connected to parts of my foot accelerator which I will now describe in detail.

5 My foot accelerator includes a foot actuatable rod or member 30 having one end projected through the floor board 12 and engageable by a foot pedal 32.

10 Mounted upon the throttle control rod 16 is a sleeve or fitting 34. I have shown the fitting 34 channel shaped in cross section and having a pair of outturned flanges 36 at one end for forming bearings. The other end of the fitting 34 is also formed with out-15 turned flanges 38 for forming bearings.

15 The foot actuatable member 30 is connected to a curved arm 40 by means of a pivotal connection as at 42. Cotter pins 44 are placed in the rod 30 above and below 20 the curved arm 40 for maintaining the proper connection between the foot actuatable rod 30 and the curved arm 40.

25 The curved arm 40 is formed with a number of spaced openings 46 which are designed to register with openings formed in the flanges 36 whereby screws or bolts 48 may be inserted therein for holding the curved arm connected to the fitting 34 and at the same time holding the fitting 34 upon 30 the throttle control 16.

35 I have shown a number of openings 46 in the arm 40 which may be selectively made to register with the openings in the bearings or flanges 36, thus enabling the position of the arm 40 upon the fitting 34 to be adjusted transversely.

40 This takes care of any variation in the position of the floor boards 12 of the automobiles which are found in the various types of Ford automobiles for which my foot accelerator is especially adaptable.

45 The fitting 34 is loose upon the rod 16 and is capable of turning or rotating there-around.

50 One end of the arm 40 is outturned as at 50 and a coil spring 52 is anchored thereto at one end and has its other end anchored around the spark control rod 24 as clearly shown in Figure 2 of the drawings.

55 The end of the fitting 34 having the flanges 38 thereon is shown as resting against a bracket 54 normally provided upon the rods 16, 22 and 24.

60 A collar 56 if necessary, may be placed around the control rod 16 above the fitting 34 for holding the fitting 34 in proper position upon the rod 16, although, the inclination of the rod 16 itself will normally cause the fitting 34 to be maintained in position against the bracket 54.

65 A throttle link arm 58 is connected to the flanges or bearings 38 by screws or bolts 60. The throttle link arm 58 takes the place of the arm 26 normally fixed to the throttle control rod 16.

One end of the throttle link arm 58 is bent upon itself as at 62 for providing a double bearing for one end of the link 28 as clearly shown in Figure 2 of the drawings. I find that in some types of the Ford car, the steering column is closer to the engine 14 than in others and consequently the links 28 are different lengths. I have therefore provided an extension 61 and openings 63 and 65 to accommodate these different length links. 70

75 The throttle link arm 58 in order to be connected to the fitting 34 includes a flange 64 positioned at right angles to the main body portion of the arm 58 which rests upon the bearings 38.

80 The flange 64 extends over the throttle control rod 16 and holds one end of the fitting 34 upon the throttle control rod 16. From the construction of the parts just described it will be noted that when the foot accelerator rod 30 is moved forwardly and downwardly in the direction indicated by the arrow 66 it will cause the arm 40 to swing in the direction indicated by the arrow 68 carrying with it the fitting 34. 85

90 The fitting 34 is thus rotated or turned upon the hand throttle control rod 16 independently of any movement of the hand throttle control rod itself.

95 Rotating the fitting 34 in the direction indicated by the arrow 68 will impart movement to the arm 58 in the direction indicated by the arrow 70. The result of this movement is to pull the throttle link 28 to a position where it will cause the throttle valve 100 of the carburetor to be operated.

100 The spring 52 returns the fitting 34 and parts mounted thereon, to its normal or predetermined position. As soon as foot pressure is removed from the foot pedal 32 then, 105 of course, the spring 52 will cause the foot accelerator to assume its normal position.

110 It will be noted that the foot accelerator is operable independent of the throttle control rod 16. In order to permit hand operation of the link 28 through the hand throttle control rod 16 I mount an angular lug 72 upon the arm 58.

115 One portion of the lug 72 has a slot 74 therein through which is extended the screw 76. Another portion of the lug 72 extends down below the arm 58 and engages the arm 26 as clearly shown in Figure 2 of the drawings.

120 The spring 52 tends to move the fitting 34 and arm 58 in a direction where the lug 72 will strike against the arm 26.

125 When the foot accelerator is operated by foot then the lug 72 simply moves away from the arm 26. When the hand throttle control rod 16 is rotated for ordinary hand manipulation of the feeding of fuel to the carburetor, then the arm 26 engaging the lug 72 swings the arm 58 in the direction indicated by the arrow 70 and this in turn ini- 130

parts the necessary movement to the link 28 for operating the carburetor throttle valve.

The necessary position of the lug 72 relative to the arm 26 may be varied by simply loosening the screw 76 and sliding the lug thereon to any necessary position and thereafter tightening the screw 76.

When it is desired to operate a throttle link connected near the upper end of the 10 throttle rod 16 by an arm 78, then it is necessary to reverse the position of the fitting 34 and the arm 56, although, the arm 40 which connects to the foot actuatable rod 30 is left in the same position.

15 The fitting 34 as shown in Figure 3 is mounted upon the control rod 16 and held against downward movement by the collar 56.

In order to change the position of the fitting 34 all that is necessary is to remove the 20 screws 48 and 60 from the arms 40 and 58 and thereafter reverse the position of the fitting 34.

It will be noted that in Figure 2, the arms 25 40 and 58 are on the same side of the fitting 34 while in Figure 3, the arm 58 projects on the opposite side from the arm 40.

30 The openings 46 in the arm 40 are such as to permit reversing of the remainder of the parts and still have the openings register with the bearings 36.

The throttle control rod 16 as shown in Figure 3 of the drawings, rotates in the direction indicated by the arrow 80 for moving the throttle link 28 in a direction indicated by the arrow 82.

35 The throttle link in this case is normally connected to the arm 78 and in my case the link 28 is connected to the arm 58 as clearly shown in Figure 3 of the drawings.

The arm 58 swings in the direction indicated by the arrow 84 for operating the 40 throttle valve and lever 18. The lug 72 is swung around so that it does not coact with the arm 78 when the arm 58 is moved in the direction indicated by the arrow 84 although, when the arm 78 is moved due to the hand 45 operation of the throttle control rod 16, then the arm 78 engages the lug 72 and causes the foot accelerator to operate.

It will be noted that in Figure 2 movement 50 of the link 28 in the direction indicated by the arrow 86 causes the operating of the throttle valve while it is the movement in an opposite direction that causes the opening 55 of the throttle valve in Figure 3.

It will be noted that my foot accelerator 60 is adaptable for use on a Ford automobile and that it is necessary in order to make the foot accelerator universal for such automobile to take care of the link 28 regardless of the direction it moves in, depending upon the particular carburetor used upon the automobile.

65 The operation of the foot actuatable mem-

ber 30 through the arm 40 whereby the fitting 34 is rotated is exactly the same in both cases.

The mounting of the levers 58 on opposite sides as illustrated in Figures 2 and 3 of the 70 drawings gives the necessary difference in movement for operating the link 28.

The lug 72 which is capable of being adjusted relative to the arms 26 and 78, enables the hand operation of the throttle control 75 rod to operate the foot accelerator and yet when the foot accelerator is operated by foot no movement of the control rod 16 is had.

It may be here mentioned that the throttle 80 control rods 16 are the same upon all types of Ford automobiles and that different styles of carburetors are operated by mounting the arm 26 near the bracket 54 in one case and mounting the arm 78 near the upper end of 85 the control rod in another case.

The fitting 34 is just half the length between the two places of mounting the arms 26 and 78 so that by simply reversing the fitting 34 and using the same parts, I am 90 able to use the same accelerator regardless of the two different positions that the arms 26 and 78 may be in.

The reversing of the parts enables the 95 foot actuatable device which consists of the rod 30 and the arm 40 to remain in the same position even though the rest of the parts of the foot accelerator are in different positions.

100 The advantage of my foot accelerator resides in the arrangement wherein the parts may be reversed and used in connection with throttle control rods having arms thereon either in the position shown in Figure 2 or the position shown in Figure 3.

105 Some changes may be made in the arrangement and construction of the various parts of my foot accelerator, without departing from the essential features and purposes of my invention, and it is my intention to cover by my claims, any modified forms of structure or use of mechanical equivalents, which may be reasonably included within their scope.

110 I claim as my invention:

1. In combination with a hand throttle control rod and a carburetor throttle control lever, of a foot accelerator including turnable means mounted upon said rod and adapted to rotate thereon, foot actuatable 115 means for rotating said turnable means, a connection between said turnable means and the throttle lever, said turnable means being reversible upon said rod relative to the foot actuatable means whereby the connection between the turnable means and throttle lever may be made in different positions relative to the foot actuatable means.

120 2. In combination with a hand throttle control rod and a carburetor throttle control 125

lever, of a foot accelerator including turnable means mounted upon said rod and adapted to rotate thereon, foot actuatable means for rotating said turnable means, a connection between said turnable means and the throttle lever, said turnable means being reversible upon said rod relative to the foot actuatable means whereby the connection between the turnable means and throttle lever may be made in two different positions relative to the foot actuatable means.

3. In combination with a hand throttle control rod and a carburetor throttle control lever, of a foot accelerator including turnable means mounted upon said rod and adapted to rotate thereon, foot actuatable means connected to one end of said turnable means for rotating said turnable means, a connection between the other end of said turnable means and the throttle lever, said turnable means being reversible end for end upon said rod relative to the foot actuatable means whereby the connection between the turnable means and throttle lever may be made in different positions relative to the foot actuatable means.

4. In combination with a hand throttle control rod adapted to either have a connection near its upper end or near its lower end with a carburetor throttle control lever, of a foot accelerator including means mounted upon said rod capable of having one end serve as either the bottom or top end and adapted to be positioned near the top or bottom end of said rod, a connection between said end and the throttle control lever and a foot actuatable member connected to the other end of said means for rotating it.

5. In combination with a hand throttle control rod and a carburetor throttle control lever, of a foot accelerator including a turnable member mounted on said rod, a foot actuatable device connected to one end of said member, a control lever operating device connected to the other end of said member, said member and control lever device being reversible without changing the position of said foot actuatable device.

6. In combination with a hand throttle control rod and a carburetor throttle control lever, of a foot accelerator including a turnable member mounted on said rod, a foot actuatable device connected to one end of said member, a control lever operating device connected to the other end of said member, said member and control lever device being reversible without changing the position of said foot actuatable device, and means for yieldingly holding said turnable member in a predetermined position relative to said rod.

7. In combination with a hand throttle control rod having an arm thereon, and a carburetor throttle control lever, of a foot

accelerator including a foot actuatable member and an arm engaging member turnably mounted on said rod, means for connecting said foot actuatable member and said arm engaging member in longitudinally spaced relation to each other, said means being reversible relative to said foot actuatable member whereby said arm engaging member may coact with the arm when spaced on either side of said foot actuatable member.

8. In combination with a hand throttle control rod having an arm thereon and a carburetor throttle control lever, of a foot accelerator including a foot actuatable member and an arm engaging member turnably mounted on said rod, yielding means actuating said foot actuatable member in one direction and means on said arm engaging member for engaging said arm in one direction whereby said yielding means will cause such engagement, means for connecting said foot actuatable member and said arm engaging member in longitudinally spaced relation to each other, said means being reversible relative to said foot actuatable member whereby said arm engaging member may coact with the arm when spaced on either side of said foot actuatable member.

9. In combination with a hand throttle control rod having an arm thereon and a carburetor throttle control lever, of a foot accelerator including a foot actuatable member and an arm engaging member turnably mounted on said rod, yielding means actuating said foot actuatable member in one direction and means on said arm engaging member for engaging said arm in one direction whereby said yielding means will cause such engagement and said foot actuatable member when actuated in the opposite direction will cause said arm engaging means to be disengaged from said arm, means for connecting said foot actuatable member and said arm engaging member in longitudinally spaced relation to each other, said means being reversible relative to said foot actuatable member whereby said arm engaging member may coact with the arm when spaced on either side of said foot actuatable member.

10. In combination with a hand throttle control rod and a carburetor throttle control lever, of a foot accelerator including a foot actuatable member turnably mounted on said rod in a fixed longitudinal position, a throttle operating means turnably mounted on said rod, means for connecting said foot actuatable member and said throttle operating means in spaced relation on said rod, said means comprising a sleeve or fitting secured to said throttle operating means and detachably secured to said foot actuatable member whereby said sleeve and said throttle operating means may be ar-

ranged to extend longitudinally on the rod in either direction from said foot actuatable member.

11. In combination with a hand throttle control rod having an arm thereon, a foot accelerator comprising a fitting or sleeve turnably mounted on said rod, a foot actuatable member secured to one end of said sleeve and laterally adjustable thereon, a throttle operating arm secured to the other end of said sleeve, means on said throttle operating arm for engaging said arm on said rod in one direction and yielding means for causing such engagement.

12. In combination with a hand throttle

control rod designed to have an arm mounted in one of two positions thereon, a foot accelerator comprising a foot actuatable member positioned substantially half way between said two positions, a member ²⁰ for engaging said arm and means for connecting said member to said foot actuatable member, said arm engaging member and said means being reversible relative to said foot actuatable member whereby said arm ²⁵ engaging member may be positioned adjacent said arm when said arm is in either of its two positions.

Des Moines, Iowa, May 20, 1926.

WALTER H. THOMAS.
